UNITED STATES PATENT OFFICE

2,558,525

WINDOW

Herman E. Reichart, Highland Park, Mich.

Application April 5, 1946, Serial No. 659,816

2 Claims. (Cl. 189—72)

1

This invention relates to improvements in windows. It is an object of the invention to provide a window which is cheap and simple to manufacture and which lends itself to mass production methods.

Another object of the invention is to provide a window wherein means are provided for firmly supporting a pane in a sash in such a manner that the pane may be easily removed and another substituted therefor.

Further objects of the invention are to provide a window wherein airtight joints are made between the sashes and their guides thus rendering weather stripping unnecessary; wherein the sashes are resiliently supported in their guides and may be moved up or down without undue effort; and wherein the use of sash cords and weights are rendered unnecessary.

Having thus briefly and broadly stated some of the objects and advantages of the invention I will now describe it in detail with the aid of the accompanying drawings, in which:

Figure 1 shows an outside elevation of my window in a building.

Figures 2 and 3 are sections on the line 2—2 and 3—3 respectively of Figure 1, on an enlarged scale.

Figure 4 is an outside elevation showing a slightly modified form of the window.

Figures 5 and 6 are enlarged sections on the lines 5—5 and 6—6 respectively of Figure 4.

Figure 7 is a detail showing one corner of the sash shown in Figures 5 and 6.

Figures 8 and 9 are enlarged partial elevations showing a top and a bottom corner respectively of the window shown in Figures 1 to 3.

Figures 10 and 11 are enlarged partial elevations showing a top and a bottom corner respectively of the modification shown in Figures 4 to 7.

Referring to the drawings, 1 designates a conventional rectangular frame consisting of four members 2 welded to one another at their adjacent extremities which are usually cut at 45 degrees as shown, and formed along the inner and outer extremities of the members are outwardly directed flanges 3 and 4 spaced a distance equal to the thickness of the wall in which the frame is to be mounted.

The parts mounted in the frame 1 may consist either of somewhat resilient steel, preferably either stainless or rustproofed, in the form shown in Figures 1 to 3 and 8 and 9, or of a suitable alloy and made according to the modified construction shown in Figures 4 to 7 and 10 and 11.

Referring first to Figures 1 to 3 and 8 and 9, mounted on the inner faces of the vertical frame members 2 and extending throughout the entire length of the latter are opposed vertical sash guides 6 each of which consists of a single piece of material having a flat portion 7 centrally of its width which rests against the said frame members. At both extremities of the flat portion 7

2

the material is folded back upon itself for a short distance as shown at 8 and is then forwardly folded to form arms 9 which terminate in transversely cupped inner and outer stile groove portions 10 and 11. The guides 6 are suitably secured to the inner faces of their respective vertical members in any suitable manner, in the present instance the members 2 are apertured and have nuts 61 welded on their outer faces; bolts 62 extend through the folded extremities of the guides 6 and through the member apertures and are in threaded engagement with the nuts 61. By thus forming the stile groove portions 10 and 11 along the opposite longitudinal margins of the guides 6 sufficient resilience is provided between opposed pairs of inner and outer stile groove portions both to support the lower and upper sashes 12 and 13 respectively at any desired height without the use of cords and sash weights and to permit vertical movement of the sashes without the exercise of undue effort.

Mounted on the inner faces of the upper and lower horizontal frame members 2 are receiving elements 14 and 15 respectively, which may be secured thereon by screws 63 in threaded engagement with nuts 64 welded to the outer faces of the said frame members. The upper receiving element 14 has a flat intermediate portion 16 which rests against the upper horizontal member 2. This portion 16 at both extremities is folded back upon itself at 17 for a short distance. From the outer fold 17 a downwardly projecting arm 18 extends and from the lower extremity of the latter a transversely cupped portion 19 extends inwardly to receive the upper margin of the upper sash 13. From the inner extremity of the cupped portion 19 an upwardly directed arm 20 extends which terminates in a foot 21 slidably upon the lower face of the flat intermediate portion 16 toward its inner folded extremity 17a which is spaced from the said foot. It will be noted that the arms 18 and 20 are downwardly somewhat inclined toward one another to render the cupped portion 19 more resilient and more readily flexible upon contact by the sash 13 when the latter is raised against it. The lower receiving element 15 is the same as the element 14 above described when turned upside down and with the cupped portion 19 in position for contact by the lower margin of the lower sash 12 when closed.

The upper and lower sashes 13 and 12 are identical in construction and each consists of four rails 22 of the same cross sectional form which are preferably cut at 45 degrees at their extremities and welded to one another. Each rail 22 consists of a relatively thin piece of steel shaped in the following manner: Intermediately of its width the rail is semi-circularly curved to form a convex back 23 the curvature of which conforms to that of the concave transversely cupped stile groove portion 10, 11, 19 or 19a which it is

to engage. Extending forwardly from opposite sides of the convex back 23 are parallel outer and inner walls 24 and 25, the former being longer than the latter and the forward edge of the inner wall extending to one longitudinal edge of the material. The outer wall 24 at its forward extremity is inwardly and rearwardly stepped at 26 and 27 respectively so that the inward step forms a bearing ledge to support one outer edge of a window pane 28. At the rearward extremity of the ledge or step 27 the material is inwardly folded to form a rest 29 which extends parallel and contiguous to one edge face of the pane 28, and extending from the inner extremity of the rest 29 is a rearwardly folded lip 30 which lies adjacent but outwardly relative to the inner wall 25 so that the rear longitudinal margin of a removable supporting plate 31 is resiliently held between the said lip and the wall 25. I prefer that the margins of the panes be mounted in suitable grooved packing strips 32 which bear against the rests 29 and are held between the ledges 27 and the movable supporting plates 31. Moreover to simplify the insertion and removal of the latter they are made somewhat shorter than the sash rails in which they are mounted.

The arrangement shown in Figures 4 to 7 and 10 and 11 is substantially the same as that already described. The vertical sash guides 6a each consist of a flat portion 7a integral with which adjacent their extremities are forwardly inclined arms 8a which terminate in transversely cupped inner and outer stile groove portions 10a and 11a. The upper and lower receiving elements 14a and 15a which are both the same include flat portions or bases 16a and a single forwardly inclined arm 18a to support the transversely cupped portion 19b.

The rails 22a forming both the upper and lower sashes 13a and 12a are again identical and each rail includes a single member having a substantially semi-circular back 23a, a forwardly projecting wall 24a flush with the outer face of the member and forming a ledge 27a along the inner side of the projection. A rest 29a for the window pane 28 is formed by the inner face of the member inwardly of the ledge 27a, and spaced inwardly of the latter a groove 33 is formed in the rail to receive a removable supporting plate 31a. The margins of the pane 28 are again preferably mounted in suitable packing strips 32a which bear against the rest 29a and are held between the ledge 27a and the removable plate 31a.

Only certain alloys are suitable for the manufacture of these sash guides 6a, upper and lower receiving elements 14a and 15a and sash rails 22a as all these parts should be somewhat resilient. The transversely cupped stile groove portions 10a and 11a should be sufficiently resilient to support the sashes without the aid of sash cords and weights and also to make sufficiently tight joints with the rounded backs of the sash rails to render weather stripping unnecessary; there should be enough give in the cupped portions 19b of the elements 14a and 15a so that a tight weather-resistant joint is made with the adjacent sash rail when the sash is closed; and the sash rail material should be such that the removable supporting plates 31a are firmly engaged in the grooves 33.

Owing to the fact that the materials preferable for use for the sash rails 22a is difficult and expensive to weld or braze, and also to reduce the weight of the rails, longitudinal apertures 35

are formed through the said rails, and their adjacent extremities are secured to one another by angle plates 36 the legs of each of which are inserted into the apertures in adjacent ends of two rails to be secured to one another, and then suitable fastening means such as the rivets 37 are then secured through each rail and the leg of the angle plates extending thereinto.

While in the foregoing the preferred embodiments of the invention have been described and shown, it is understood that further alterations and modifications may be made thereto provided the said alterations and modifications fall within the scope of the appended claims.

15 What I claim is:

1. A double hung window sash construction consisting of vertical sash guides and slideable sashes cooperating therewith, each guide having a base for attachment to a window frame, forwardly projecting arms integral with each guide extending from the base adjacent the inner and outer sides of the latter, and a transversely cupped stile groove portion having a concave bearing surface extending from and integral with the forward extremity of each arm throughout the length of the latter, the stile groove portions on each guide being in transverse alignment and spaced from and adjacent one another for independent movement at a position in advance of said base, each stile groove portion on one guide being opposite on stile groove portion on the other guide and said stile groove portions and their arms being resilient so as to urge said sashes into close engagement with each other, each sash 20 including vertical rails having convex backs the curvature of which corresponds to that of the cupped stile groove portions mounted for vertical movement in and resiliently and frictionally engaged between opposed pairs of transversely cupped stile groove portions said rails being so seated in said stile groove portions that the said stiles engage each other so as to effect a sealing contact therebetween.

2. A double hung window sash construction 25 consisting of sash guides and slideable sashes cooperating therewith, said sashes including horizontal rails, the rails being slideable in the guides, a unitary horizontal receiving element including a flat portion for attachment to a horizontal 30 face of a window frame, an arm forwardly inclined from said flat portion, and a transversely cupped stile groove portion having a concave bearing face extending over said flat portion, said concave bearing face being spaced from said flat portion, said stile groove portion extending from the forward extremity of said arm for resilient engagement by the back of one horizontal rail of the sash, said back being of transversely convex form to correspond with the curvature 35 of said stile groove.
